UNITED STATES PATENT OFFICE

GUST JOHNSON, OF ORRIN, NORTH DAKOTA

DRAFT EQUALIZER

Application filed July 12, 1926. Serial No. 121,952.

The object of this invention is to provide a draft equalizer comprising a main draft evener, a supplemental draft evener, connected therewith in the manner disclosed, a doubletree and singletrees connected with one end of the supplemental draft evener, with particular means for connecting another doubletree and singletrees with the supplemental evening device.

With the foregoing and other objects in view, the invention consists in the novel construction and arrangement of elements described, illustrated and claimed, it being understood that modifications may be made within the scope of the claims without departing from the spirit of the invention.

In the drawings forming part of this application,

Figure 1 is a top plan view.

Figure 2 is a view in vertical section on line 2—2 of Figure 1.

Figure 3 is a view in vertical section on line 3—3 of Figure 1.

Figure 4 is a fragmentary view of the rear portion of the structure of Figure 1.

Figure 5 is a detail view, in elevation, of the loop member and the mounting means therefor, this device appearing in Figure 1, at the left, in top plan.

Figure 6 is a detail view, with part broken away, showing the position of the chain with reference to adjacent elements, this chain passing thru the loop member of Figure 5.

Figure 7 is a top plan view of an equalizer designed for use with five draft animals.

Figure 8 is a view in elevation of the central portion of the long or supplemental evener, at the central portion of Figure 7.

The main evener includes a somewhat heavy transverse element or bar 10, and metallic plates 11 and 12 extend respectively on the upper and lower sides of element 10, and are connected by member 13, these portions 11, 12 and 13 forming parts of an integral construction.

Element 10 may be cut away, as shown at 14, and a space 15 is provided between the left end of element 10, as illustrated in Figure 3, and the U-portion 13, a pulley wheel 16 be-

ing mounted within the space thus provided, and being carried by a pivotal member 17.

A clevis 18 is secured by means of bolt 19, the latter passing thru the forked portion 18' of the clevis, and also passing thru bar 10 and plates 11 and 12. Bar 10 is cut away centrally as shown in Figure 3, and upper and lower bars 20 and 21 extend into the cutaway portion, and are secured by bolt 19.

A chain 23 passes around pulley wheel 16 and thru the space between bars 20 and 21, the latter being connected with supplemental evener 25 by means of a bolt 26. While members 20 may be connected at various points between the ends of eveners 11 and 25, in the embodiment of the invention illustrated they are shown as connected substantially at the center of the evener 11 and extending at right angles to said eveners. Supplemental evener 25 carries at one end thereof a U-shaped strap 27 providing a loop thru which chain 23 passes, and the latter passes around pulley wheel 28 and is secured at 29 to the end of element 25, at the left of Figure 1.

Pulley wheel 28 is mounted between plates 29^a, one being shown in Figure 1, and these elements 29^a are secured to doubletree 30, to which singletrees 31 and 32 are connected in any well known manner.

Another doubletree 33 is secured by bars such as 34 to the right hand end of supplemental evener 25, and singletrees 36 and 37 are connected with doubletree 33.

A brace or braces, such as 38 are connected pivotally at 39 with the main evener, and are also connected pivotally with the supplemental evener 25, at a point between bolt 26 and the right hand end of evener 25.

One of the principal objects being to reduce side draft, and also to equalize the draft, the length of element 25, and the point of pivotal connection between this element and bar or bars 38 is important. By way of illustration, brace or bar 38 is secured in Figure 1 by bolt 40 positioned as shown, that is inwardly from the bolt 34', and between the latter and bolt 26. The chain 23 is secured at the same point 40 by a clevis 23^a as shown in Figure 100

1, and when the proportions there shown are carried out, the distance between the point where chain 23 is connected at 29 and bolt 26 is twice the distance between the point or bolt last named and the bolt 40 securing the 5 other end of the chain 23 and the brace or braces 38. In practice the distance between bolt 40 and bolt 34' is one and substantially one-third times the distance between bolts 26 and 40. The relative position of the connecting elements disclosed may be varied sufficiently to meet such conditions as may develop. For instance, clevis 23^a could be connected to bolt 26 or 34', the distance from bolts 26 to 40 being correspondingly changed. If 10 clevis 23^a is connected to bolt 34', the distance from bolt 26 to bolt 40 should be one-third of the distance from bolt 26 to bolt 34'. If 15 clevis 23^a is connected to bolt 26, the distance from bolts 26 to 40 should be two-thirds of the distance from bolt 19 to bolt 39.

In the modified construction shown in Figures 7 and 8, wherein provision is made for five draft animals, the front or supplemental 20 evener is designated 50, the main draft evener is shown at 51, and the clevis being designated 25 53. The bar or bars 52 connect the eveners and may be placed at various points between the ends thereof.

30 A doubletree 54 has connection with singletrees 55 and 56, and doubletree 54 has connected therewith a pulley wheel 57 carrying chain 58, one end of this chain being connected at 59 with the left end of supplemental evener 50.

35 Chain 58 passes around pulley wheel 58' and thence around a central pulley wheel 60 secured by bolt 61 passing thru element or elements 62 and thru supplemental evener 50. Chain 58 is connected with singletree 63 and the latter is positioned between doubletree 54 and doubletree 64 having connected therewith singletrees 65 and 66. Doubletree 64 is connected by bars such as 67 and bolt 68 with supplemental evener 50.

40 In the illustration of Figure 7, and in Figure 8, the supplemental evener 50 comprises upper and lower metallic plates extending the full length of the intermediate heavy bar 50 constituting the evening device per se. The strap or loop member 50^a at the left is formed by a U-shaped bend in the upper and lower bars or plates 50' and 50'' of the supplemental evener.

45 In Figure 7 the distance between point 59 where chain 58 is secured to element 50, and bolt 61' is twice the distance between the bolt 61' and the bolt 68 by means of which the doubletree 64 is secured,—it being understood that half of the pull on the doubletree 54 is applied at 59.

The bolt 61' connects brace 70 with the evener 50. Brace or bar 70 is connected with 65 evener 51 by bolt 71, the points of connection

of bar or bars (or braces) 70 being as illustrated, or being varied to suit particular conditions.

The distance between bolts 61 and 61' may be regarded as three times the distance between points 61' and a point designated for convenience as 73, opposite bolt 71. The distance between bolt 74 and the point 58' may be regarded as three-fifths of the effective length of the main evener 51, and the distance between bolt 74 and bolt 71 may be regarded as two-fifths of the effective length of element 51. These proportions indicated, or other approximate proportions contribute to the effectiveness of the device in reducing side draft and in providing the equalizing effect desired. In practice the length of elements 20 and 52 will be substantially one-half the length of the main evener. The distance here referred to is the distance between the bolts by which the connections are made. It will be obvious that the device shown in Figs. 7 and 8 which is shown as a five-horse device, could readily be made into a four-horse device by connecting the end of chain 58 to any of the bolts 61, 61' or 68, and omitting the singletree 63. If the chain 58 is connected to bolt 61' the distance between bolts 61 and 61' should be three-fifths of the distance between bolts 74 and 71. If the end of chain 58 is connected to bolt 68, the distance between bolt 61 and 61' should be one-half the distance between bolts 74 and 71. If the end of chain 58 is connected to bolt 61, the parts will be as shown in Figs. 7 and 8.

50 From the above description it is seen that applicant has provided a very simple and efficient form of draft equalizer. While the preferred embodiments of the invention have been illustrated and described, it will be obvious that changes in the proportions of the various parts can be made. For instance, the main evener 11 shown in Fig. 1 could be divided with the portion to the left of member 20 being one-sixth longer than the portion to the right, instead of these parts being substantially the same as shown in Fig. 1. It will, of course, be understood that the distance between bolts 26 and 40 will still be proportioned relative to the length of the short end of the main evener. Thus, if clevis 23^a is connected to bolt 40 as shown in Fig. 1, the distance between bolts 26 and 40 will be one-half the length of the short end of the main evener, if clevis 23^a is connected to bolt 26 the distance between bolts 26 and 40 will be two-thirds of the length of the short end of the main evener and if clevis 23^a is connected to bolt 34', the distance between bolts 26 and 40 will be one-sixth less than one-half of the length of the short end of the main evener.

55 This application relates to improvements over the structure disclosed in my pending application, Serial No. 114,569, filed June 8, 130

1926, in that it provides for five draft animals instead of four, and that it illustrates the chain or flexible member connected with the front evener at a different point from the 5 point shown in that application, and in application Serial No. 118,571, filed June 25, 1926.

Having described the invention, what is claimed is:—

10 1. In a draft equalizer, a main evener, a second evener of greater length, means extending between and connected to said eveners by pivots, said eveners being swingable about said pivots, a pulley wheel at one end 15 of the main evener, draft means, a chain connected with one end of the second evener and with the draft means and passing around said pulley wheel on the main evener, a second pulley wheel carried by the second evener between its ends, the chain passing over the second pulley wheel, draft means connected with this portion of the chain, and draft means connected with the end of the second evener remote from the end connected 25 with the chain.

2. In a draft equalizer, a main evener, a second evener of greater length than the main evener, means connecting said evener at a plurality of points, a pulley wheel at one end 30 of the main evener, a doubletree, a chain connected with one end of the second evener and with the doubletree and passing around said pulley wheel on the main evener, a second pulley wheel, carried by the second evener between its ends, the chain passing over the second pulley wheel, a singletree connected 35 with this portion of the chain, in advance of the second evener, and a doubletree connected with the end of the second evener remote 40 from the end connected with the chain.

3. In a draft equalizer, a main evener, a second evener, means connecting the eveners at points between the ends thereof, means connected with one end of the main evener 45 and with the second evener between the end thereof and the point of connection of the means first named, a flexible member operatively connected with the second evener substantially at the point of connection of said 50 first mentioned means, a pulley wheel on the other end of the main evener, a doubletree, a second pulley wheel connected therewith, said flexible member passing over these pulley wheels and being connected with the second 55 evener at one end of said flexible member, and a second doubletree connected with the second evener.

4. In a draft equalizer, a main evener, a second evener, means connecting the eveners 60 at points between the ends thereof, means connected with one end of the main evener and with the second evener between the end thereof and the point of connection with the means first named, a chain operatively connected 65 with the second evener adjacent to

the point where the first named connecting means are secured thereto, one end of the second evener being of greater length than the corresponding portion of the main evener on the same side of the central portion of the eveners, a pulley wheel on the other end of the main evener, a doubletree, a second pulley wheel thereon, the chain passing over these pulley wheels and being connected with the second evener at one end of said chain, 70 and a second doubletree connected with the second evener.

5. In a draft equalizer, a main evener, a second evener of greater length, a plurality of means connecting said eveners, a pulley 80 wheel at one end of the main evener, draft means, a chain having one end connected to the second evener and movably connected with the draft means and passing around said pulley wheel on the main evener, a second pulley wheel carried by the second evener between its ends, the chain passing over the second pulley wheel, draft means connected with this portion of the chain, and draft means connected with the end of the second 85 evener remote from the end connected with the chain.

6. A draft equalizer comprising a main evener, a second evener, a plurality of rigid means extending between and connected by 90 pivots to said eveners, said eveners being swingable about said pivots, a pulley wheel carried by said main evener, draft means, a chain having one end connected to the second evener and movably connected with the draft means, and passing around said pulley wheel on the main evener, a second pulley wheel carried by the second evener, said chain passing over said second pulley wheel and draft means connected with this portion of the 95 chain in front of the second evener.

GUST JOHNSON.
